UNITED STATES PATENT OFFICE.

CHARLES H. MORGAN, OF WORCESTER, MASSACHUSETTS.

GAS-PRODUCER.

No. 902,432.

Specification of Letters Patent.

Patented Oct. 27, 1908.

Application filed June 13, 1906. Serial No. 321,529.

To all whom it may concern:

Be it known that I, CHARLES H. MORGAN, a citizen of the United States, residing at Worcester, in the county of Worcester and 5 Commonwealth of Massachusetts, have invented a new and useful Improvement in Gas-Producers, of which the following is a specification, accompanied by drawings forming a part of the same, in which—

0 Figure 1 is a central vertical sectional view through the gas producer. Fig. 2 represents a top view of a gas producer embodying my invention, with a portion of the top plate removed, and Fig. 3 is a detailed sectional 5 view on an enlarged scale of the upper end of the air pipe and its surrounding socket.

Similar reference letters and figures refer to similar parts in the different views.

My invention relates to an improved device for feeding air to the concentric twyer of a "suction" or "downdraft" gas producer located at the upper end of the gas producing chamber, by which I accomplish increased ease of repairs combined with 5 strength of construction, and it consists in the construction and arrangement of parts as hereinafter described and pointed out in the annexed claims.

Referring to the accompanying drawings 0 1 denotes a combustion or gas producing chamber having side walls 2 and 3, and a cover which consists of a metal plate 4 provided with manholes 5 having covers 6, through which manholes 5 the coal is supplied to the combustion chamber 1. At the center of the plate 4 is an opening 7 provided with a supporting flange 8 upon which is held a removable twyer 9 of fireclay or other refractory material. Above the cover 4 is a 5 top plate 10 supported on an annular vertical flange 11 of the gas producing chamber, and provided with a central opening 12 having a cover 13, of sufficient size to enable the twyer 9 to be removed through the opening 12 and a new one inserted. The manholes 5 also extend through openings in the top plate 10, and the top plate 10 and covers 6 and 13 are provided at their edges with depending flanges which are sand sealed by a layer of sand as is usual in gas producers of this class.

Between the side walls 2 and 3 of the gas producing chamber an annular space 14 is inclosed which communicates with the bottom of the gas producing chamber 1 through openings 15, thereby affording a passage for

the gas generated in the chamber 1 to the gas outlet 16.

The cover 4 closes the annular space 14 at the top, and is depressed to form an annular recess 17 provided with openings which receive the upper ends of a series of pipes 18 detachably held at their lower ends by screw threads or otherwise in a corresponding series of openings in a plate 19 which closes 65 the bottom of the annular space 14. The annular recess 17 is filled around the ends of the pipe 18 with a layer of asbestos *a* covered by a layer of sand. Below the annular space 14 and the outer wall 3 is an annular 70 water receptacle 20 communicating with the pipes 18 and containing water at a predetermined level below the lower ends of the pipes 18, thereby allowing air to pass upwardly through the pipes into the space 21 75 inclosed between the top plate 10 and the cover 4, and as the inclosed air space 21 communicates with the twyer 9 a supply of air is furnished to the combustion chamber 1.

The operation of my improved gas producer is as follows:—The air enters below the outer wall 3, and passing over the water in the trough 20 ascends through the pipes 18 to the space 21 between the cover 4 and the top plate 10, from thence it passes 85 through the twyer 9 to maintain the combustion of the coal in the chamber 1. Water is supplied in the form of a spray against the inner sides of the pipes 18 by means of pipes 22, and the surplus water not 90 taken up by the current of air in the form of steam is caught by the water receptacle 20. This furnishes a supply of steam to the ascending current of air which is also thoroughly heated as it passes through the pipes 95 18, which are entirely surrounded by the hot gas in its passage from the combustion chamber 1 to the gas outlet 16.

I am aware that it is not new to pass the air for a downdraft gas producer through 100 an annular space between outer and inner walls of the producer and in proximity to a similar annular space for the passage of the heated gas. The passage of the air current through a series of pipes accomplishes the 105 separation of the air from the heated gas and also increases the surface contact of the air conduits with the gas. At the same time the pipes may be easily removed and replaced from the top. I also provide 110 means for supporting a depending removable twyer at the top of the combustion

chamber which may be readily replaced when necessary. The overflow of water from the water receptacle is received by the ash pit 23 in which a water level is maintained by an overflow pipe 24 sufficient to water seal the lower edge 25 of the producer.

I claim,

1. In a gas producer, the combination with a gas producing chamber having an

10 annular space surrounding said chamber, means for admitting gas from said chamber to said annular space, and a twyer for supplying air to the interior of said chamber, of a series of air pipes within said annular 15 space, said pipes communicating with the outside air at one end and arranged to supply air to the twyer at the other end.

2. In a gas producer, the combination with a gas producing chamber having an

20 annular space surrounding said chamber, means for admitting gas from said chamber to said annular space, and a twyer for supplying air to the interior of said chamber, of a series of pipes within said annular space, 25 said pipes communicating with the outside air at one end and arranged to supply air to the twyer at the other end, and means for mixing steam with the air as it passes through the series of pipes.

3. In a gas producer, the combination with a gas producing chamber having a surrounding annular space, means for admitting gas from said chamber to said annular

35 space, and a twyer for supplying air to the top of said gas producing chamber, of a series of vertical air pipes detachably held within said annular space and arranged to admit air at the lower end of said pipes and to deliver it to the twyer from the upper

40 end of said pipes.

4. In a gas producer, the combination with a gas producing chamber having an annular space surrounding said chamber, and a twyer depending from the cover of

45 said gas producing chamber, of a series of pipes within said annular space arranged to admit air at the lower end of said pipes and to deliver it to the twyer at the upper

end of said pipes, means for admitting water to said pipes, and an annular water receptacle below the lower end of said pipes.

5. In a gas producer, the combination with a gas producing chamber having a wall, of an outer wall surrounding the wall of said chamber inclosing an annular space between said walls, with openings from said chamber into said annular space for the admission of gas, and an opening for conducting the gas away from said annular space, means for closing the ends of said annular space, air pipes passing through said annular space and detachably held therein, said pipes communicating with the outside air at their lower ends and with a twyer at their upper ends and a twyer for admitting air to the gas producing chamber.

6. In a gas producer, the combination with a gas producing chamber, having an annular space in its side walls, means for conducting the gas from said chamber through said annular space, a cover, and a top plate above said cover inclosing an air space, a twyer communicating with said air space, and a series of air pipes inclosed in said annular space, with the lower ends of 75 said pipes communicating with the outside air and their upper ends communicating with said air space.

7. In a gas producer, the combination with a gas producing chamber having an inclosed annular space in its side walls, means for admitting gas from said chamber to said annular space, a cover for said annular space, a series of air pipes inclosed in said annular space and communicating at their 85 lower ends with the outside air, with their upper ends projecting through said cover, a twyer for admitting air to said gas producing chamber, means for conducting air from the upper ends of said air pipes to said 90 twyer, and a recess in said cover to admit packing around said air pipes.

CHAS. H. MORGAN.
